UNITED STATES PATENT OFFICE.

JOHN W. JACKSON, OF ST. LOUIS, MISSOURI.

STEAM WASHING-MACHINE.

1,136,808.

Specification of Letters Patent. Patented Apr. 20, 1915.

Application filed December 6, 1912. Serial No. 735,210.

To all whom it may concern:

Be it known that I, JOHN W. JACKSON, a citizen of the United States, and residing at St. Louis, in the State of Missouri, have invented certain new and useful Improvements in Steam Washing-Machines, of which the following is a specification.

This invention relates to washing machines and more particularly to washing machines of that type in which the water is drawn back and forth through the clothes in order to clean them.

One of the objects of this invention is to provide a novel arrangement of the clothes container or boiler and the stove body so that the boiler may be readily removed without causing the top of the stove body to be left open.

Another object is to provide a novel form of diaphragm or false bottom which will promote the circulation of the water and steam in the container or boiler as the clothes are being washed and boiled.

Another object is to provide novel driving means for the plunger which is so arranged on the cover of the container that the stress will be transmitted over a large area, so that the sheet metal cover will not break at the points of support of the driving means.

Another object is to provide a novel form of plunger which will coöperate with the diaphragm to further promote the circulation of the water and steam through the clothes, and agitate the clothes.

Further objects will appear from the detail description taken in connection with the accompanying drawings, in which:

Figure 1 is a front elevation of a washing machine embodying this invention, Fig. 2 is a section on the line 2—2 Fig. 1, Fig. 3 is an enlarged cross section through the cover showing the driving mechanism in elevation, Fig. 4 is a plan view of the diaphragm, Fig. 5 is a plan view of the plunger head, the plunger rod being shown in section, and Fig. 6 is an enlarged section on the line 6—6 Fig. 5.

Referring to the accompanying drawings 50 10 designates a stove body which may be constructed of sheet metal, and which has a bottom 11 connected by a flange 13 with the stove body, and 12 designates the feet for supporting the stove body. A casting 14 55 forming the stove front supports the fire and ash-pit doors 15 and 16 respectively. The stove is provided with the usual grate

17 and with a stove pipe connection 18. A plate 19 having a flange 20 is secured to the stove body at a point a short distance 60 below the top of the body by means of rivets 21 extending through the stove body and the flange. This plate therefore forms an upper wall which is sunk a short distance below the top of the stove body so that the 65 sides extend a short distance above the upper wall.

A container or boiler 22 of sheet metal is adapted to rest on the plate or wall 19 and within the side walls of the stove body and 70 is provided with a cover 23 hinged at 24 and having a latch 25 for securing it in closed position. A diaphragm 26 having an inclined flange 27 rests upon the bottom of the container so as to form a false bottom 75 therefor. The body of this diaphragm has a comparatively large central perforation or aperture 28 and a series of (in this case four) comparatively large perforations 29. The flange 27 is provided with a large number 80 of comparatively small perforations 30 extending entirely around the circumference of the diaphragm. The diaphragm is made of sheet metal and is provided with strengthening ribs 31. The diaphragm fits 85 loosely in the container or boiler, and in order to hold it in position the boiler is beaded as shown at 32, the bead extending inwardly a sufficient distance so that when the edge of the flange snaps past it the diaphragm will be held loosely in position on 90 the bottom of the boiler. The container has a drain cock 55, and the stove body is provided with a slot 56 receiving the shank of the cock and permitting removal of the 95 container from the stove body.

The plunger 33 has a series of conical plunger heads 34. These plunger heads are preferably made of sheet metal and are secured to the plunger by means of rivets 35 100 as shown in Fig. 6. The edge of the plunger head is turned over as shown at 36 so as to form a smooth edge which will not tear the clothes. The plunger head is perforated at its upper end as shown at 37, the 105 perforations inclining downwardly for the purpose hereinafter to be described.

The plunger has a plunger rod 38 which extends through a flanged bushing 39 secured on the inside of the cover, and 110 through a guide 40 formed on the yoke of a bracket 41 mounted on the upper side of the cover. The rod 38 has a slot 42 which is engaged by a set screw 43 so as to prevent the

rod and the plunger from turning, and the rod is also provided with a knob or handle 44 so that the plunger may be raised or lowered by hand.

5 The bracket 41 has a bearing for a pinion 45 which has a crank pin connection 46 with a pitman or link 47. The other end of the link is connected with a sleeve 48 slideable upon the rod 38 and having a clamping screw 49 engaging the slot 42 in the rod. The sleeve 48 is thus prevented from turning on the rod and may be clamped in any suitable position thereon. The pinion 45 meshes with a gear 50 of a larger diameter 15 mounted on a drive shaft 51 having at one end a bearing in the bracket 41 and at its other end a bearing in a bracket 52 mounted on the cover. This drive shaft 51 is provided with a handle 53 whereby it may be 20 turned.

The operation of the machine is as follows: Rotation of the shaft 51 through the handle 53 will cause a reciprocation of the plunger, and in view of the fact that the gear 50 is of larger diameter than the gear 45 the reciprocation of the plunger is rapid. When the water in the container or boiler becomes heated the water and steam will flow and circulate down the outside walls, 30 down through the apertures 30 in the flange 27, and up through the apertures 28 and 29 in the diaphragm, as shown by the arrows in Fig. 2. Such a circulation takes place when the plunger is stationary, *i. e.*, when 35 the clothes are being boiled. When the plunger is reciprocated the plunger heads will act as pumps to draw and force the water back and forth through the clothes. As the plunger moves up the water will be 40 drawn up through the apertures 28 and 29 and down through the apertures 30 so that the circulation will take place in the directions of the arrows, Fig. 2. When the plunger moves down the direction of flow will 45 be reversed. As these plunger heads move down on the clothes and the water covering the same, the water will splash up into these heads and will be forced out of the apertures 37, and since these apertures are inclined downwardly the water will be thrown 50 forcibly on top of the clothes. As the plunger heads rise they will act by suction to draw the water upwardly through the clothes. It will therefore be seen that while 55 the plunger is operated the water is drawn back and forth through the clothes to thoroughly clean the same, but while the clothes are boiling the water will circulate upwardly at the center and downwardly along 60 the sides. In order to adjust the plungers to any amount of clothes in the container, the sleeve 48 is loosened and the plunger is dropped down on the clothes. The parts

are now moved to the position shown in Figs. 1 and 3 with the crank pin connection 65 46 on its lower dead center. The sleeve is now clamped to the rod, and when so adjusted will be in effective operative position.

The invention thus accomplishes its objects. The water will be drawn and circulated through the clothes both when the plunger is operated and when at a stand still while boiling. A plunger head is positioned above each aperture 28, 29, in the diaphragm body. The ribs 31 also divide 70 the diaphragm into a plurality of compartments, one below each plunger head. This results in a uniform and efficient circulation. The connection of the driving mechanism to the cover is over a large area so that these 75 connections will not work or tear loose when the machine is used for any length of time. When the container or boiler is removed from the stove body the stove is not left open but is closed by the wall or plate 19 so 80 that the smoke will not escape into the room. The stove body walls projecting above the plate 19 also operate to retain the container in position during the operation of the washing means, while the drain cock will 85 hold the container against turning. The stove body may then be used also for heating laundry irons and the like.

It is obvious that various changes may be made in details of construction within the 95 scope of the claims without departing from this invention, and it is therefore to be understood that this invention is not to be limited to the specific construction shown and described.

Having thus described the invention what is claimed is:

A washing machine comprising a container, a diaphragm in said container, said diaphragm having a plurality of apertures 105 in the body thereof and having a plurality of apertures at its circumference, a plunger head mounted in said container above said diaphragm, ribs on the under side of said diaphragm dividing the same into a plurality of compartments corresponding to the apertures in the body thereof, a plurality of plungers on said plunger head with a plunger positioned above each aperture and compartment in the diaphragm body, and 110 means for reciprocating said plunger head, adapted to cause a circulation in said container upwardly in the center and downwardly at the sides and vice versa.

In testimony whereof I affix my signature 120 in the presence of two witnesses.

JOHN W. JACKSON.
